APPARATUS FOR DRYING WET GRANULAR MATERIALS

Gustave Andre Vissac, Calgary, Alberta, Canada

Application October 31, 1938, Serial No. 238,046

7 Claims. (Cl. 34—38)

This invention relates to improvements in apparatus for drying wet granular materials.

Different methods and apparatus for effecting the drying of wet granular materials have been suggested and used heretofore. However, the methods and apparatus previously employed have had serious disadvantages, the chief of which is the great waste of heat in drying the materials. This waste of heat makes the drying of materials unduly costly. Another disadvantage of the known devices is that there is not sufficient control of the temperature of the hot gases used to dry the granular materials, which results in many cases in damage to the materials treated, particularly in the case of coal, which cracks and oxidizes when subjected to hot gases above a certain temperature.

It is an object of the present invention to provide a novel apparatus for drying wet granular materials, including coal, so as to avoid apparent disadvantages in previously used apparatus and to provide in a simple manner means for the drying of material quickly and efficiently.

A further object of the invention is to provide an apparatus which may be operated with the use of a large volume of air, at the lowest possible temperature, wherein the air is caused readily to penetrate the bed of material being dried without affecting the movement of the material to any extent.

A further object of the invention is to provide an apparatus wherein heated gases may be employed for penetrating the bed of material to absorb the moisture.

A still further object is the provision of an apparatus including novel and simple flexible joints between the moving and stationary parts thereof.

A still further object is the provision of an apparatus including means for utilizing heat normally lost to preheat the materials to be dried.

Yet another object is the provision of an apparatus of the character described which is completely automatic in its operation.

The present invention consists essentially of one or more shaking screens for receiving and agitating the material to be dried, a hood disposed above each screen for projecting a heating and drying medium on to the material, at least one hopper below each screen underlying the hood thereof, an air chamber below the hopper or hoppers communicating therewith, means connected with the air chamber for inducing pulsating air current to draw the heating and drying medium through the agitated bed of material as

it moves along the screen, means for circulating water through the air chamber to remove heat from the heating and drying medium as it travels therethrough, means for spraying the heated water on to the materials before they are treated, 5 and means for automatically controlling the temperature and quantity of the heating and drying medium projected on to the materials on the screen or screens, as more fully described in the following specification and illustrated in the accompanying drawings in which

Figure 1 is a side view, partly in section, of the apparatus for drying the materials.

Figure 2 is a sectional view taken on the line 2—2 of Figure 1.

Figure 3 is a plan view taken on the line 3—3 of Figure 1, with certain parts broken away.

Figure 4 is an enlarged detail view, partly in section, of a flexible coupling.

Figure 5 is an enlarged sectional detail of one 20 end of the air chambers of the apparatus,

Figure 6 is an enlarged sectional detail of one 25 end of a screen, and

Figure 7 is a diagrammatic side elevation of the 30 complete apparatus.

Referring more particularly to the drawings, 35 10 and 11 indicate two inclined compensating shaker screens supported by suitable oscillatable hangers 12 and 13 respectively, on each side thereof, suspended from beams 14 secured to vertical supports 15. The screens are preferably covered with wire mesh, perforated plates or wedge wire screen surfaces of proper mesh and are connected to a crank shaft 16 through connecting rods 17 disposed at an 180° angle, so 40 that when the crank shaft 16 is operated through any suitable source of power, the screens are subjected to opposed and continuous oscillation.

The wet granular material is delivered from a chute 20 on to screen 10 which is divided into 45 two sections 21 and 22 extending longitudinally thereof. The material, after passing over screen 10, is transferred to screen 11 and this latter screen is likewise divided into two sections 23 and 24 extending longitudinally thereof. A pair 50 of hoppers 25 are suspended from the screen 10 underlying approximately one half said screen and another pair of hoppers 26 are suspended from the screen and underlie approximately the other half thereof. One set of hoppers 25 and 26 55 are disposed beneath the section 21 of the screen 10 while the other set of said hoppers are disposed beneath the section 22 of the screen. Each of said hoppers is provided with a short discharge pipe 27 at the outlet opening in the bottom there- 55

of. Similarly, a pair of hoppers 28 are suspended from the screen 11 underlying substantially one half said screen and another pair of hoppers 30 are suspended from the screen and underlie substantially the other half thereof, with one set of hoppers 28 and 30 disposed beneath the section 23 of said screen and the other set of hoppers disposed beneath the section 24 of the screen. Each of the hoppers 28 and 30 is provided with a short discharge pipe 31 at the outlet opening in the bottom thereof. The hoppers under the screens 10 and 11 are arranged in the same manner.

In Figure 1, only one of each of the hoppers 25, 26, 28 and 30 is shown, the first two in elevation and the other two in section. Figure 2 shows the position of the pair of hoppers 26 in relation to the screen 10, the remaining pairs of hoppers being similarly disposed with regard to their respective screens.

A hood 32 is mounted on and overlies substantially the whole of the screen 10 and a hood 33 is mounted on and overlies the screen 11 in a similar manner. The hoods 32 and 33 are provided with inlet openings 34 and 35, respectively, in the tops thereof. An inverted V-shaped baffle plate 36 extends transversely of the hood 33 beneath the inlet opening 35 thereof and above the screen 11 while a similar baffle plate 37, see Figure 2, extends transversely of the hood 32 beneath the inlet opening 34 thereof and above the screen 10. Counterbalanced flaps 40 are mounted at each end of both of the hoods 32 and 33. Each flap 40 is pivotally suspended from its hood and is provided with a weighted counterbalancing arm 41 and at its lower or trailing edge with a strip 42 formed of canvas or other suitable material, see Fig. 6. The trailing edges of these flaps rest upon the granular materials as they pass thereunder and said materials, now dried, are discharged from the screen 11 on to a discharge chute 43.

A pair of tapered air chambers 44 and 45 are situated side by side beneath the hoppers 25, 26, 28 and 30, which chambers communicate at their forward ends respectively with sections 46 and 47 of a pulsator 48. Blades 50 and 51, disposed at an angle of 90° with respect to each other, are mounted in the sections 46 and 47 respectively, of the pulsator 48, said blades being rotated by a suitable source of power (not shown), which source of power preferably having a variable speed drive. A passage 52, see Fig. 7, connects both sections of the pulsator 48 with gas circulating means, such as an exhaust fan 53, having an exhaust pipe 54, said fan being operated by a suitable source of power (not shown), which source may be the same as that operating the pulsator 48.

The air chamber 44 has a plurality of inlet openings 55 formed in the top thereof, one for each hopper, disposed beneath the screens 10 and 11, and a sleeve 56 extending upwardly from each of said openings. The sleeves 56 are larger than the discharge pipes 27 and 31 of the hoppers 25, 26, 28 and 30, so that the pipes fit into the sleeves without touching the sides thereof. From the description so far, it will be seen that the hoppers oscillate with the screen while the air chamber is stationary so that it is necessary to provide a flexible coupling therebetween.

Figure 4 is an enlarged detail of the coupling between the discharge pipe 27 of the hopper 26 and the adjacent sleeve 56 of the air chamber 44.

All these couplings are the same so one only need be fully described. Referring particularly to Figure 4, the upper end of the sleeve 56 is sloped so that it lies at a tangent to an imaginary circle drawn with its centre coinciding with the upper pivoting point of the hanger 12 (Fig. 1) immediately thereabove. A flange 57 is formed around and extends outwardly from the upper end of the sleeve 56, which flange lies in the same plane as said sloped upper end. A sliding plate 58 is slidably mounted on a bearing plate 60 which, in turn, is secured to the flange 57. As a result of this construction, the sliding plate 58 lies at a tangent to an imaginary circle with its centre coinciding with the upper pivoting point of the hanger 12 above mentioned. This sliding plate is free to slide on the bearing plate 60 between the latter and rollers 61 held thereabove by supports 62 which are mounted on the edge of the flange 57 and extend upwardly past the bearing plate 60. An opening 63 is formed in the sliding plate 58 centrally thereof, said opening being slightly larger than the discharge pipe of the hopper 26 which projects therethrough. When the hopper oscillates with the screen 10, both a vertical and a lateral motion is imparted thereto so that the discharge thereof moves through an arc, the centre of which is the upper pivot point of the hanger 12 referred to above.

In Fig. 4, the hopper is shown in full lines in one extreme position and in dot and dash lines in the other extreme position. The sliding plate serves as a flexible coupling to prevent gases from passing from the sleeve 56 to the atmosphere outside the device or air from entering the device. The sliding plate 58 moves laterally with the hopper while it permits said hopper to move in a vertical direction. This coupling is very effective and efficient without the disadvantages of the known types of flexible couplings. The constant flexing of the ordinary metal couplings causes the metal to crystallize while couplings of canvas or rubber rapidly tear or deteriorate.

The air chamber 45 is also provided with a plurality of inlet openings 64 and upwardly extending sleeves 65, each of which is provided with a flexible coupling as described, between it and the discharge pipes of the hoppers extending thereinto.

Each of the inlet openings 34 and 35 of the hoods 32 and 33 is surrounded by a sleeve 67 extending upwardly from said opening, the upper end of which is sloped at the same angle as the upper ends of the sleeves 56 and 65 of the air chambers 44 and 45. Pipes 68 extend downwardly into the sleeves 67 from a main pipe 70, said pipes 68 being smaller than the sleeves so that they do not touch the sides thereof. Flexible couplings similar to those described are provided between the sleeves 67 and the pipes 68. These couplings function in the same manner as the previous couplings, the only difference being that the sleeves on which the plates 58 are mounted oscillate while the pipes 68 are stationary. It will be seen that a vertical and lateral motion is imparted to the sleeves by the hoods 32 and 33 which oscillate with the screens 10 and 11.

The main pipe 70 is connected to a flue 71 of a furnace 72 (see Fig. 7) which is provided with an automatically controlled blower 73. Dampers 74 and 75 are provided in the flue and in the pipe 70, respectively, by means of which the hot gases from the furnace may be directed through either the pipe 70 or the flue 71, as desired. A cold air

pipe 76 is connected to the main pipe 70 between the flue 71 and the first pipe 68.

A damper 71 mounted in the pipe 70 between the flue 71 and the cold air pipe 76, is operatively connected by a rod 78 to a modulating motor 80 which is governed by a temperature controller 81 mounted in the passage 52. Another damper 82 mounted in the pipe 76, is operatively connected by a rod 83 to a modulating motor 84 which is governed by a temperature controller 85 mounted in the pipe 70 between the cold air pipe 76 and the first pipe 68 leading to the hood 32.

Pipes 86 and 87 extend downwardly from the air chambers 44 and 45, respectively, adjacent the discharge ends thereof, and said pipes may, if desired, be provided with pulsators 88 and 90 operated by a common shaft 91 which is operatively connected to the pulsator 48 or to its source of power, in any suitable manner. The blades of these pulsators are set at right angles to each other. The pipes 86 and 87 extend below the surface of the water in a reservoir 92, the level of which water is maintained constant by weirs 93. Drain pipes 94 extend downwardly from the pulsator 48 below the surface of the water in the reservoir 92. The water flows from said reservoir over the weir 93 into a sump 95. Another drain pipe 96 extends downwardly from the exhaust fan 53 below the surface of the water in the sump 95. A pump 97 is adapted to pump water from the sump along either or both pipes 98 and 100, the flow of water being controlled by valves 101 and 102. The pipe 98 extends over a chute 103 and terminates in a spray device 104 so that the granular materials are sprayed with water as they pass along said chute 103 to the chute 20. The pipe 100 extends along to the ends of the air chambers 44 and 45 lying at the discharge end of the apparatus, where it is divided into pipes 105 and 106, one extending into each air chamber as a jet. If desired, each pipe 105 and 106 may be divided into upper and lower sections, see Fig. 7, so that water may be supplied to the air chambers and the tops and bottoms thereof. Valves 107 and 108 may be mounted in each pipe 105 and 106. If necessary, a water supply pipe 110 having a control valve 111, may be connected to the system at any desired point, such as to the pipe 100, as shown.

The wet granular material to be treated, say, for example, coal, passes through the chute 103 where it is preheated by warm water from the spray 104, on to the chute 20 whence it is delivered to the shaker screen 10. The inclined shaker screens 10 and 11 are subjected to opposed and continuous oscillation, during which time the coal passes over the screen 10 and on to the screen 11, whence it is discharged into the discharge chute 43. During its travel over these screens, the coal is constantly subjected to substantially alternate vertical and horizontal movement. The horizontal movement causes the coal to move towards the discharge ends of the screens and, at the same time, the vertical movement continually loosens up said coal.

When the damper 74 is closed and the dampers 75 and 77 are open, hot gases are drawn from the furnace 12 through the flue 71, along the main pipe 70 and down through the pipes 68 into the hoods 32 and 33 in which they are dispersed laterally by the baffle plates 37 and 36. These gases pass through the bed of coal on the screens. The hot gases serve further to warm the coal and the condensed moisture thereof is shaken off and eliminated so that by the time the coal reaches

the discharge end of the screen 11, it is thoroughly dried. The gases and moisture are drawn through the pairs of hoppers 25, 26, 28 and 30 into the air chambers 44 and 45 where most of the moisture is condensed and deposited while the cooled gases are drawn through the sections 46 and 47 of the pulsator 48 and along the passage 52 by the exhaust fan 53, whence they are discharged through the exhaust pipe 54.

As previously described, the screen 10 is divided longitudinally into two sections 21 and 22 while the screen 11 is also divided into two longitudinal sections 23 and 24. The sections 21 and 23 of these screens communicate through the hoppers 25, 26, 28 and 30 therebeneath with the air chamber 44 and the sections 22 and 24 communicate through the hoppers 25, 26, 28 and 30 therebeneath with the air chamber 45. The blades 50 and 51 of the pulsator 48 are arranged at right angles to each other so that the air chambers 44 and 45 and, consequently, the hoppers connected thereto alternately communicate with the gas circulating means or exhaust fan 53. With this arrangement, direct connection is alternately established and disestablished between the fan and the hoppers beneath each side of the screens so that the hot gases are drawn through the bed of coal on one side only of the screens 10 and 11 at any one particular time. By alternately interrupting the flow of gases through the bed of coal on each side of the screens in this manner, the coal is alternately loosened up on each side of the screens by the oscillation thereof. A steady flow of gases through the coal would tend to counteract the loosening effect of the screen movement, thus allowing the coal to pack. This loosening of the coal is further aided by the fact that when the pulsator closes one of the air chambers, a back surge is created in that chamber so that the gases are forced upwardly through the coal. This not only assists in loosening the coal but the gases are recirculated through the coal more completely to dry it.

Most of the moisture removed from the coal is condensed in the air chambers 44 and 45 whence it passes through the pipes 86 and 87 into the reservoir 92 and over the weirs 93 into the sump 95. If desired, the pipes 86 and 87 may be provided with pulsators 88 and 90, the purpose of which will hereinafter appear. Any moisture condensed in the pulsator 48 passes through the drain pipes 94 into the reservoir 92 and over the weir 93 into the sump 95, while any moisture condensed in the fan 53 is directed to the sump through the drain pipe 96. It might be added here that a large percentage of the heat remaining in the gases after they have passed through the coal, is absorbed by the water in the air chambers. The warmed water is pumped from the sump 95 by the pump 97 through the pipe 98 to the spray 104 where it is brought into contact with the coal passing along the chute 103. From this it will be seen that, after having passed through the coal, the greater part of the heat from the gases normally lost, is conveyed to the coal being supplied to the apparatus, to preheat it. This is very advantageous because it is much easier to dry heated materials than cold materials and yet no extra original heat energy is necessary for this purpose.

At the same time, water may be pumped from the sump through the pipe 100 and the pipes 105 and 106 back to the air chambers 44 and 45. This water may be pumped steadily through the air chambers, in which case, being considerably

cooler than the gases therein, it condenses the moisture removed from the coal, washes the fines passing through the screens out of the air chambers, and absorbs the greater part of the heat from the gases to be used to preheat the coal supplied to the apparatus, as described above. However, if the pulsators 88 and 90 in the pipes 86 and 87 are employed, their blades are set at right angles to each other and they are set so that the pipe 86 of the air chamber 44 is closed when the blade 50 of the pulsator 48 closes the outlet end of said air chamber. Alternately, the pipe 87 of the air chamber 45 is closed when the blade 51 of the pulsator 48 closes the discharge end of said air chamber. In this way, the water alternately and intermittently rises in the air chambers 44 and 45 when the discharge ends thereof are closed. This increases the above described back surges of the gases at predetermined intervals, to provide for a thorough recirculation of the gases through the bed of coal alternately on each side thereof. This also increases the loosening effect of the back surges of the gases on the coal.

As previously described, the sliding plates 58 permit the hoods and hoppers to oscillate in relation respectively to the air chambers and the pipes 68 and at the same time provide an effective seal to prevent the hot gases from escaping therefrom. The counterbalanced flaps 41 at each end of the shaker screens permit the coal to move along the screens and yet they prevent the hot gases from escaping and air from entering at the ends of the hoods.

As a rule the gases from a furnace are too hot for use in drying coal since the latter starts to crack and oxidize at about 400° F. so that with bituminous coal it is not safe to use gases at temperatures above 600° F. or 700° F. The temperature controller 85 may be set at, say 600° F., with the result that any variations will act on the motor 84 to open or close the damper 82 in the cold air pipe 76 to maintain the gases supplied to the coal beds at a desired temperature.

The exhaust fan 53 operates at a constant speed and under normal conditions may, for example, induce 40,000 cu. ft. of hot gases at 600° F. into the apparatus, which gases, after accomplishing their necessary work in the dryer, may come out at, say 120° F. In this case the temperature controller 81 may be set at 120° F. Should the coal contain less moisture, a smaller amount of heat will be absorbed in the dryer for the evaporation of this moisture so that the temperature of the gases passing through the passage 52 will rise. In this case, the temperature controller 81 will act on the motor 80 to cause the damper 77 in the pipe 70 to be partly closed. As a result of this, the control 83 will cause the damper 82 to close correspondingly. This means an increased resistance in the fan circuit, hence a drop in volume, for example, to 35,000 cu. ft. of hot gases at 600° F. circulating through the dryer, which is sufficient to dry the coal. Similarly, a change of resistance from the bed of coal on the screens, due to different coarseness or volume, will act in the same way automatically to control the volume and temperature of the gases supplied to the beds.

This apparatus may be made completely automatic in operation by the use of any of the well known types of automatic stoker with the furnace 72.

It is apparent upon consideration of the foregoing that the apparatus provides for preheating

the coal to be treated by means of heat normally wasted and for efficiently drying said coal. In addition the apparatus is particularly efficient through the novel means for retaining the hot gases therein and through the automatic control of the temperature and volume of gases supplied to the coal beds.

However, it will be realized that while coal has been used as a general illustration of the material treated, the apparatus is generally applicable to the drying of a wide variety of materials.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. Apparatus for drying wet granular material, comprising a shaking screen for receiving and agitating the material, a hopper disposed below said screen, a hood disposed above the screen in an area overlying the hopper, means for introducing hot gases to the hood, gas circulating means, an air chamber connected between the hopper and the gas circulating means, pulsating means for establishing and disestablishing direct connection between the gas circulating means and the hopper, said circulating means being adapted intermittently to draw the gases through the material on the screen, and means for creating a flow of water through the air chamber to remove heat from the gases passing therethrough, and means for bringing at least some of the heated water into contact with the material being treated to preheat said material.

2. Apparatus for drying wet granular material, comprising a shaking screen for receiving and agitating the material, a hopper disposed below said screen, a hood disposed above the screen in an area overlying the hopper, means for introducing hot gases to the hood, gas circulating means, an air chamber connected between the hopper and the gas circulating means, pulsating means for establishing and disestablishing direct connection between the gas circulating means and the hopper, said circulating means being adapted intermittently to draw the gases through the material on the screen, means for creating a flow of water through the air chamber, and means for intermittently interrupting said flow of water through the air chamber to create a back pressure through the material on the screen at predetermined intervals.

3. Apparatus for drying wet granular material, comprising a shaking screen for receiving and agitating the material, a hopper disposed below said screen, a hood disposed above the screen in an area overlying the hopper, means for introducing hot gases to the hood, gas circulating means, an air chamber connected between the hopper and the gas circulating means, pulsating means for establishing and disestablishing direct connection between the gas circulating means and the hopper, said circulating means being adapted intermittently to draw the gases through the material on the screen, means for creating a flow of water through the air chamber to remove heat from the gases passing therethrough, pulsating means for intermittently interrupting said flow of water through the air chamber to create a back pressure through the material on the screen at predetermined intervals.

the screen at predetermined intervals, and means for bringing at least some of the heated water into contact with the material being treated to preheat said material.

- 5 4. Apparatus for drying wet granular material comprising a shaking screen for receiving and agitating the material, a plurality of hoppers disposed below the screen underlying each side thereof, a hood disposed above the screen in an area overlying the hoppers, gas circulating means, a pair of air chambers, each chamber being connected to the hoppers underlying one side of the screens and to the gas circulating means, pulsating means for establishing and dis-
10 establishing direct connection alternately between the gas circulating means and the hoppers under each side of the screen, means for introducing hot gases to the hood whereby said gases are directed alternately through the material on each side of the screen and to the gas circulating means, pulsating means for establishing and dis-
15 establishing direct connection alternately between the gas circulating means and the hoppers under each side of the screen, means for introducing hot gases to the hood whereby said gases are directed alternately through the material on each side of the screen, and means for creating a back pressure alternately in the air chambers.

20 5. An apparatus as claimed in claim 4 including means for creating a flow of water through each air chamber, and pulsating means for alternately interrupting the flow of water through the air chambers, said pulsating means interrupting the flow of water in each chamber when the connection between the chamber and the gas circulating means is disestablished whereby a back pressure is created through the material on the side of the screen overlying the air chamber.

25 6. Apparatus for drying wet granular material comprising a plurality of shaking screens for receiving and agitating the material, a plurality of hoppers disposed below the screens underlying each side thereof, a hood disposed above each

screen in an area overlying the hoppers there-
beneath, gas circulating means, a pair of tapered air chambers, each chamber being connected to the hoppers underlying one side of the screens and to the gas circulating means, pulsating means for establishing and disestablishing direct connection alternately between the gas circulat-
10 ing means and the hoppers under each side of the screens, counterbalanced flaps at the ends of each screen adapted to permit the material to move thereunder, means for introducing hot gases to the hoods whereby said gases are directed alternately through the material on each side of the screens while said material advances therealong, and means for creating a back pres-
15 sure in each air chamber when the connection between the chamber and the gas circulating means is disestablished.

7. Apparatus for drying wet granular material, comprising a shaking screen for receiving and agitating the material, at least one hopper ar-
20 ranged below the screen, at least one hood dis-
posed above the screen in an area overlying the hopper, means for introducing hot gases to the hood for absorbing moisture from the material, gas circulating means, an air chamber connected between the hopper and the gas circulating means, means for establishing and disestablishing direct connection between the gas circulat-
25 ing means and the hopper, said circulating means being adapted intermittently to draw the gases through the material on the screen, and means for circulating water through the chamber to assist in condensing the moisture from the gases
30 as they pass therethrough.

35 GUSTAVE ANDRE VISSAC.
